Peter Stahl & John Dieffenbacher of Turbot Township, Penn,

Letters Patent.

The schedule referred to in these Letters Patent and making part of the same, containing a description in the words of the said Peter Stahl & John Dieffenbacher themselves of their improvement in the Plough

To all to whom these presents shall come,

Be it known that we Peter Stahl & John Dieffenbacher both of Turbot township in the County of Northumberland and State of Pennsylvania have invented, a new and useful improvement in the Plough and that the following is a full and exact description of the construction and operation of the said Machine as invented or improved by us. The Plough is for the purpose of cultivating Corn and Potatoes, and consists of two beams A, B, fastened together in a triangular manner, into each of which are fastened securely three standards C, D, E, F, G, H, on the lower end of each of which are iron shears or mould board is securely fastened, and the whole placed in such a manner in relation to each other, that when the plough is drawn along over the row of corn or potatoes there will be three of the abovesigned shears or mould board, on each side of the said row, the two first or foremost ones, I, J, throwing the earth up against the corn, the two second or next K, L, throwing the earth which is before them into the furrows caused by the two first and the last or third shears M, N, throwing the earth which is before them into the furrow caused by the two second

On the top of the Plough a tongue O. is securely fastened extending beyond the plough a sufficient length to allow, of two horses being attached thereto, one on each side for the purpose of drawing and guiding the same; and also on the hinder part of the Plough two handles P, Q, are placed for the convenience of the ploughman in regulating and using the same for the purposes designed,

Each of the beams should be made about three feet three inches

in length, about three by four inches thick, and joined together by two bars, one at each end of the plough, the foremost one R. being about three inches wide and two and a half inches thick, and of such a length as to bring the heel of the two fore cheers or mould boards about fourteen inches apart, — and the hindmost bar S. being of the same thickness as the fore one, and of such a length as to bring the heel of the two hindmost cheers or mould boards about three feet apart, — The Standards C. D. C. F. G. H. should each extend about twenty-one inches from the bottom of the beam, and be joined into the latter as to stand forward at the bottom about two and a half inches from a perpendicular line to the beam; and should be about one and three quarters of an inch thick, and about six inches wide. The iron shears or mould boards should be about eight inches long and about five inches deep fastened on to the standards by two screws passing through each, and of such a shape, and placed in such a manner upon the four sides of the lower ends of the standards, so that when the plough is drawn by the hoes in a line, with, and over the rows of corn or potatoe, the earth, before each will be thrown toward the said rows. For a particular idea of the shape & relative situation of the cheers and standards reference can be had to the model, the inclination of the face of each of the standards ^{however} should be at an angle of about fifteen degrees to the outside of the beam, or in other words at an angle of about eighty degrees in relation to each other on the two sides of the plough. The tongue O. is fastened to the centre of each of the cross bars R. & S. and should be about ten and a half feet in the whole length, and about three inches square, at the hindmost end and about two and a half inches in diameter at the fore end, It should be placed nearly horizontal, but raised or lowered as occasion may require, by means of a small block, which can be placed either under or in the upper side of the tongue and secured in either situation by means of a draw bolt, which

passes through the same and secures them to the centre of the post or R, each handle should be fastened to the hindmost bar and to the middle standard of each beam both inclining to left side of the plough the left handle being about two and a half feet and the right one about three feet in length. The horses should be attached to the plough by means of a double tree fastened in the lower side of the tongue at of What we claim as our own invention and not previously known in the above described machine, are first the sheers or mould boards (which are each cast in one piece and forming a cheer & mould board) second, the high standards C, D, E, F, G, H, which carry the plough beams so far above the corn or potatoe as not to break it down so long as it needs cultivating. But that the placing them in such a manner as to plough or cultivate both sides of a row of corn or potatoe at one and the same time of going over the same, we do not restrict the number etc. of sheers or mould board and standards to three on each side of the plough as their number must be increased or diminished as the distance between the rows of corn or potatoe is increased or diminished
